UNITED STATES PATENT OFFICE.

MARCUS HOOPS, OF SPRINGVIEW, NEBRASKA.

MEANS TO PREVENT FREEZING OF THE WATER-COOLING SYSTEMS OF AUTOMOBILES.

1,265,782.

Specification of Letters Patent. Patented May 14, 1918.

Application filed May 24, 1917. Serial No. 170,693.

To all whom it may concern:

Be it known that I, MARCUS HOOPS, a citizen of the United States, residing at Springview, Nebraska, in the county of Keyapaha and State of Nebraska, have invented certain new and useful Improvements in Means to Prevent Freezing of the Water-Cooling Systems of Automobiles, of which the following is a specification.

10 This invention relates to means to prevent freezing of the water cooling systems of automobiles.

One object of my invention is to provide an appliance which may be readily installed 15 in automobiles or other motor driven vehicles for the purpose of facilitating the circulation of water in the water cooling system and to prevent freezing of the water in cold weather.

20 Another object resides in the provision of an appliance of the nature stated, embodying among other characteristics, means whereby the products of combustion from the engine may be utilized for the purpose 25 of heating the water in the water cooled system of the engine to prevent freezing of the water in cold weather and which is so constructed that the products of combustion utilized for the said purpose may be directed 30 through the usual exhaust of automobiles so that the appliance need not be dismounted in warm weather.

With the above and other objects in view, the present invention consists in the combination and arrangement of parts herein-after more fully described, illustrated in the accompanying drawings and particularly pointed out in the appended claims, it being understood that changes may be made in the 40 form, size, proportion and minor details without departing from the spirit or sacrificing any of the advantages of the invention.

In the drawings:—

45 Figure 1 is a side elevation of one embodiment of the invention;

Fig. 2 is a top plan view;

Fig. 3 is another side elevation;

Fig. 4 is a detail sectional view of the 50 auxiliary heating chamber;

Fig. 5 is a side elevation of another embodiment of the invention;

Fig. 6 is a side elevation of the second embodiment of the invention; and

55 Fig. 7 is a front view of the second embodiment of the invention.

Referring now to the accompanying drawings, and more particularly to Figs. 1 to 4, inclusive, the reference character 10 indicates an engine of an automobile or other motor vehicle which has water pipe connection 11 and 12 with the radiator casing 13, the water pipe connection 12 having an outlet valve 14 whereby the radiator may be drained when desired. 65

I propose to heat the water in the radiator and consequently throughout the water heating system of automobiles and the like to prevent freezing of the water in cold weather, especially in the radiator, by the 70 application of heat to the lower portion of the radiator.

In one embodiment of my invention, I secure a heating chamber 15 to the radiator casing 13, preferably against the inner side 75 of the radiator casing. As shown, this heating chamber 15 may be of a length substantially the width of the radiator casing and it may be secured to the radiator casing in any suitable manner, and as shown, I locate 80 said chamber at the inner side of the radiator adjacent the lower portion thereof. A plate 16 is disposed against the outer side of the radiator at the lower portion thereof. This plate 16 is of a width and length substantially the same as the width and length 85 of the heating chamber 15. Through this plate 16 and through the radiator casing and the heating chamber 15, suitable bolts 17 may be passed in order to secure said plate 90 and said heating chamber firmly to the lower portion of the radiator casing. The particular arrangement of this plate 16 and the heating chamber 15 provides for a dead air space 15' at the bottom of the radiator casing, keeping out drafts of cold air and facilitating heating of the lower portion of the 95 radiator.

As a heating medium, I utilize the products of combustion from the engine, connecting to the exhaust manifold 18 of the engine 10, suitable pipe connections 19 which establish communication between the exhaust manifold 18 and one end of the heating chamber 15. 100

Valves 20 and 21 are located in the exhaust manifold 18 for the purpose of regulating the supply of the exhaust gases to the heating chamber 15 and these valves are adapted to be operated by the driver of the 110 vehicle by means located on the dash 22 of the vehicle. For instance, the valves 20 and

21 have arms 23 and 24 respectively, which are connected together by means of a link 25 pivotally connected thereto, there being a push rod 26 connected to the pivotal joint between the arm 23 of the valve 20 and the connecting link 25, said push rod 26 extending through the dash 22 and having an operating knob or handle 27, as shown. These valves are mounted and arranged with relation to each other so that when one valve is closed, the other valve is opened. In cold weather the valve 21 is opened to allow the hot gases from the exhaust pipe to go forward into the heating chamber 15. When this valve 21 is open to permit the exhaust gases to go forwardly to the heating chamber 15, the valve 20 is closed to cut off the flow of exhaust gases through the exhaust 28.

The hot gases passing into the heating chamber 15 flow through the heating chamber from one end to the other thereof and exhaust from the end opposite the end through which the hot gases are admitted to said chamber. At the exhaust end of the chamber are two exhaust pipes 29 and 30 which straddle the water pipe 12 and which are connected at their outer ends by a Y or other suitable coupling 31 from which leads a single exhaust pipe 32 to exhaust the products of combustion to the atmosphere.

An auxiliary heating chamber surrounds the exhaust pipes 29 and 30 and also the lower portion of the water pipe 12. This auxiliary heating chamber retains the heat radiating from the exhaust pipes 29 and 30, facilitating the application of heat to the water cooling system of the engine. This auxiliary heating chamber may be of any suitable construction, but as shown, it is formed of upper and lower sections 33 and 34, respectively, each section being of substantially semi-circular form in cross section and each having flanges 35 whereby the sections may be bolted together. The lower section 34 is longer than the upper section 33 and at its front end extends under the radiator to the extreme lower portion of the water pipe 12, there being an opening 36 in the section 34 to permit projection therethrough of the pet cock or outlet valve 14. An opening 37 is formed in the upper section 33 to permit passage of the water pipe 12, there being an opening 32 at the rear of the auxiliary heating chamber for the passage of the pipe 32. The heat radiating from the exhaust pipes 29 and 30 being retained in the auxiliary heating chamber obviously cooperates with the heating chamber 15 to facilitate the heating of the water and to prevent freezing in cold weather.

In warm weather it may be desired to remove from the machine the parts hereinbefore described, and if so, the exhaust pipe 18 may be plugged, by means of a suitable plug (not shown) at the point α in the ex-

haust manifold 18. It might be stated, however, that my invention hereinbefore described need not be removed from the machine, but permitted to remain on the machine because by closing the valve 21, the connection between the valve 21 and the valve 20 will result in the valve 20 being opened so that in warm weather, the products of combustion may pass backward through the common exhaust 28.

In another embodiment of my invention, the radiator 13 is provided with a lower water chamber 38, there being suitable water conducting passages 39 and 40 between the engine and the radiator and the lower water chamber 38, respectively, as shown. From this water chamber 38 leads a valve or pet cock 41. To the under side of the water chamber 38 I secure one form of my heating chamber 42 which may be secured to the radiator in any suitable manner, but as shown, by means of suitable clips 43. The products of combustion are let into the heating chamber 42 at one end through pipe connections from the exhaust manifold pipe in the same manner as in the form first described. In this second form of the invention, however, there is but one exhaust pipe leading from the heating chamber 42 and this exhaust pipe is indicated at 44 and 95 leads from the end of the heating chamber opposite the end at which the products of combustion or exhaust gases enter said chamber. This outlet 44 of the heating chamber 42 leads into an auxiliary heating chamber 45 which surrounds a portion of the water pipe 40 to further heat the water in the water system of the machine and the products of combustion entering the auxiliary heating chamber 45 exhausts therefrom through a short pipe 46. A muffler (not shown) may be secured to the pipes 32 and 46, if desired.

In both forms of my invention, it will be understood that the same may be readily applied to automobiles and readily disconnected therefrom and that without removal of the appliance from the machine the products of combustion may be prevented from passing to its heating chambers, but directed through the usual common muffler or exhaust, by means of push rod 26 on dash.

What I claim is:

1. An appliance for preventing the freezing of automobile radiators and water pipe connections comprising an engine, a radiator casing, a heating chamber located adjacent the radiator casing, means for diverting the exhaust gases of the engine to one end of said chamber, an exhaust means connected to the opposite end of said chamber, and an auxiliary heating chamber located adjacent the aforesaid heating chamber and coacting with said exhaust means as and for the purposes set forth.

2. An appliance for preventing freezing of automobile radiators and water pipe connections comprising an engine, a radiator casing, a heating chamber located adjacent the radiator casing, water pipe connections between the engine and radiator casing, a passage between the exhaust of the engine and one end of said chamber so as to divert the exhaust gases of the engine into said chamber, means connected to the chamber to convey the exhaust gases therefrom, an auxiliary heating chamber located adjacent the aforesaid heating chamber and coacting with said exhaust means, and means for cutting off the supply of exhaust gases to said first mentioned heating chamber. 60
3. An appliance for preventing the freezing of automobile radiators and water pipe connections, comprising an engine, a radiator casing, a heating chamber located adjacent the radiator casing at the inner side of the latter and at the lower portion thereof, a plate disposed adjacent the lower portion of the radiator casing at the front thereof, means connecting said plate and said chamber to clamp them against the outer and inner sides of the radiator casing to support them in position and to provide a dead air space at the lower portion of the radiator casing, means for conveying the exhaust gases of the engine to said chamber, and an exhaust conveying means connected to the chamber to convey the exhaust gases from said chamber to the atmosphere. 70
4. An appliance for preventing the freezing of automobile radiators and water pipe connections comprising an engine, a radiator casing, a heating chamber secured to the inner side of the radiator casing at the lower portion thereof, means for conveying the exhaust gases from the engine to said chamber at one end thereof, means whereby the exhaust gases may be exhausted from said chamber at the end opposite the end at which the exhaust gases are admitted thereto, and an auxiliary heating chamber adjacent to the main heating chamber and inclosing portions of the water pipe connections and the exhaust conveying means. 80
5. An appliance for preventing freezing of automobile radiators and water pipe connections comprising an engine, a radiator casing, a heating chamber secured to the inner side of the radiator casing at the lower portion thereof, means for conveying the exhaust gases from the engine to said chamber at one end thereof, spaced valves located in the terminal portions of said manifold, and means for opening and closing said valves alternately, the heating chamber having an exhaust. 90
6. An appliance for preventing the freezing of automobile radiators and water pipe connections comprising an engine including an exhaust manifold, a radiator casing, a heating chamber located adjacent the radiator chamber, means connected with one end of the exhaust manifold for conveying the exhaust gases from the exhaust manifold of the engine to said chamber, spaced valves located in the terminal portions of said manifold, and means for opening and closing said valves alternately, the heating chamber having an exhaust. 100
7. An appliance for preventing the freezing of automobile radiators and water pipe connections comprising an engine, a radiator casing, pipes connecting the water cooling system of the engine and said radiator, means for utilizing the exhaust gases of the engine to heat the water in the radiator, and a heating chamber connected with and deriving its heat from the exhaust of the aforesaid heating means and arranged to heat the water in one of said connecting pipes between the water cooling system of the engine and the radiator. 105
8. An appliance for preventing the freezing of automobile radiators and water pipe connections comprising an engine having an exhaust manifold adapted to discharge exhaust gases at either end, a radiator casing, a heating chamber located adjacent the radiator casing at the lower portion of the latter, means for diverting the exhaust gases of the engine to one end of said chamber, means whereby the exhaust gases may be exhausted from said chamber, means for utilizing the heat radiating from said exhaust means of the chamber to apply heat to a portion of the water cooling system of the engine, and valves located in the terminal portions of the exhaust manifold for controlling the discharge of exhaust gases. 110

In testimony whereof I affix my signature.

MARCUS HOOPS.
